UNITED STATES PATENT OFFICE.

JOHN R. WOOD, OF HATBORO, PENNSYLVANIA, ASSIGNOR TO THE NEW PROCESS MULTI-CASTINGS COMPANY, INCORPORATED, OF NEWARK, NEW JERSEY, A CORPORATION OF NEW JERSEY.

MOLDING MACHINE.

Application filed November 3, 1925. Serial No. 66,472.

The present invention relates to a machine for making molds and more particularly to a multiple machine adapted for the making at the same time of the cope and drag of a 5 mold with matched part patterns or for making a plurality of molds more or less simultaneously with match plate patterns, one on each of the units of the multiple machine. The invention further relates to 10 means for handling the mold parts for the discharge thereof from the flask parts and for their assembly.

Reference is hereby made to my copending application Serial Number 33,603, filed May 15 29, 1925, which shows and describes a unit machine for the making of cope and drag with a match plate and of which machine the machine of the present invention comprises a plurality.

20 In the drawings there is shown an embodiment of the machine of my invention in which:

Fig. 1 is a front elevation view in part section showing a machine having two 25 hydraulic presses, flask part support and pattern plate support means, means for bringing the flask part and pattern plate over desired presses, mold pressing heads, and mold and pattern parts,

30 Fig. 2 is an end view in elevation of the machine of Fig. 1,

Fig. 3 is a view similar to Fig. 2 but of the opposite end,

Fig. 4 is a plan view of the machine,

35 Fig. 5 is a detail view in part section of bearings between supporting and moving parts, and

40 Fig. 6 is a vertical midsection view showing a part for supporting a flask part or pattern plate for vertical movement and for rotational movement about a horizontal axis.

In the drawings the base 1 mounted on the 45 wheels 2, 2 carries at its center the fixed vertical hollow post 4. At the base of said column 4 is joined the bearing block 6 which has the lateral annular bearing grooves 7, 7 and the top annular bearing grooves 8, 8 for which, respectively, are provided the ball bearings 10, 11. About the bearing block 50 6 is mounted the supporting and bearing cap

12 which has annular grooves 14, 15 corresponding to grooves 10, 11.

Fixed to said cap 12 are the two vertical columns 15 and 15' which are diametrically opposite each other and which are secured together at their tops by the ring 16 which extends about said column 4, suitable bearing surfaces being provided therebetween to permit rotational movement.

Riding on ring 16 is the ring 18 with the 60 ball bearings 20, 20 therebetween. The cap ring 21 fixed to column 4 by the bolts 22, 22 serves to hold ring 18 in position, ball bearings 23, 23 being provided between ring 18 and cap 21 to permit said ring 18 to rotate about column 4. To the arms 24, 24 extending in diametrically opposite directions from ring 18 are hinged at 25 the arms 26, 26 through each of which extends the screws 28, 28 each of which carries at its lower end 70 a squeeze head 30. A handle 32 extending downwardly from the end of each of arms 26, 26 and serves to move said heads 30 upwardly on hinges 25, 25. Fixed to a cable 34 which is attached to the outer end of arm 75 26 and passes over a pulley 35 mounted on ring 18 and into hollow column 4 is a weight 33 which serves to counter balance said arm 26 and squeeze head 30. The lower end of each of the handles 32, 32 passes through 80 an opening 35 in a bracket 36 fixed one to each end of said base 1, and a nut 38 serves to hold handle 32 and head 30 against upward movement when desired.

From the foregoing description it can be 85 seen that the columns 15 and 15' may be rotated about column 4 and that the squeeze heads 30, 30 are rotatable on column 4 and separately from the rotation of said columns 15, 15.

On said base 1 near each end thereof is mounted a hydraulic press 40, one under each of said squeeze heads 30, 30. Suitable pipe connections 42, 42 and control valves 44 therefor are provided for the presses, 90 pressure being supplied through hoses or pipes not shown which connect them to a suitable source.

Said columns 15, 15' carry slides 45, 45', one on each and which have mounted there- 100

on respectively the heads 46, 46' and which are rotatable on the ball bearings 82, 82 about a horizontal axis (see Fig. 6), the stops 48, 48 serving on each to lock them in position. The splines 47, 47 on columns 15, 15' fit in corresponding ways in slides 45, 45' and hold said slides against rotation on said columns 15 and 15'. The head 46 has mounted thereon the cope 50 which is pivoted for horizontal movement thereon and the head 46' has mounted thereon the match part 52 of a pattern which is pivoted for horizontal movement. At the upper end of each of slides 45, 45' is formed a hook 54 which is adapted to cooperate with the hook 56 which is pivoted to a ring 58 mounted on each of said columns 15, 15' near the top thereof. A cam 60 and a handle 62 therefor serve to engage and disengage hook 54 from hook 56 when desired. A match part 64 for matching part 52 is positioned on the table 66 of press 40 and a drag 68 is mounted on table 66'.

In the use and operation of the above described machine a cope mold and a drag mold are formed either by jolting or squeezing in a manner well known in the art in the cope 50 and the drag 68, respectively. After the two parts of the mold are made the cope 50 is separated from the match part 64 and the match part 52 is separated from drag 68, the tables 66, 66' and the hooks 54, 56 being used respectively to raise and suspend the parts. The columns 15, 15' on cap 12 are rotated about column 4 to bring cope 50 and the cope mold therein over the drag 68. The table 66' is then raised to bring the pins 70, 70 of drag 68 into engagement with corresponding holes in flanges 72, 72 on cope 50 and to bring drag 68 against cope 50. The handles 75, 75 on the cope mold retaining slides not shown but known in the art and particularly described in my co-pending application Serial Number 33,605, filed May 29, 1925, are moved to release the cope mold whereupon the table 66' is lowered to bring the drag and drag mold down and to bring with them the cope mold. A cover such as is known in the art may then be positioned over the cope mold and secured to the flask and the unit removed for the pouring of metal into the mold. The cope 50 is then returned to its position over table 66.

If a cover for the cope mold and drag mold together is used then the cope and drag when brought together are secured to each other, the cope mold retaining slides released through handles 75, 75 and the table 66' lowered to bring the cope and drag mold properly positioned together out of the flask. The cover is then put on and secured to the bottom board 80 and removed from the machine.

In the use and operation of the two sides

of the machine separately for making complete molds on each press a cope mold is mounted one to each of said heads 46 and 46' and moved into the inverted position. A pattern plate and a drag being properly positioned on the inverted cope and secured thereto and the whole supported on the corresponding press table. Mold material is then sifted into the drag and jolted or squeezed down. A bottom board is then secured to the drag and the flask is rotated on the head 46 or 46' into the upright position whereupon the cope mold is filled with mold material which is jolted or squeezed. The cope is then hung by hooks 54, 56 and the cope and drag released from each, the drag and pattern plate lowered by the table and the pattern plate removed. The drag is then raised into engagement with the cope and the cope mold released by means of handles 75, 75 and either the cope or both the cope and drag are removed from the finished mold in the manner above described.

What I claim is:

1. In a mold making machine, in combination, a plurality of sub-machines each comprising a support for a flask or pattern part permitting vertical movement of the part and movement thereof about a horizontal axis, means for moving a part mounted on said support upward, means for suspending the part above said moving means and means for bringing the part supported on one sub-machine above the moving means of another sub-machine. 90

2. In a mold making machine, in combination, a plurality of sub-machines each comprising a support for a flask or pattern part permitting vertical movement of the part, means for moving a part mounted on said support upward, means for suspending the part above said moving means, and means for bringing the part supported on one sub-machine above the moving means of another sub-machine. 95

3. In a mold making machine, in combination, a plurality of sub-machines each comprising a support for a flask or pattern part permitting vertical movement of the part and movement thereof about a horizontal axis, means for moving a part mounted on said support upward, means for suspending the part above said moving means, means for bringing the part supported on one sub-machine above the moving means of another sub-machine, and a squeeze head above said supported part when over its moving means. 110

4. In a mold making machine, in combination, a plurality of sub-machines each comprising a support for a flask or pattern part permitting vertical movement of the part and movement thereof about a horizontal axis, means for moving a part mounted on said support upward, means for suspending the part above said moving means, 125

means for bringing the part supported on one sub-machine above the moving means of another sub-machine, and a squeeze head above said supported part when over its moving means, said moving means being adapted for either jolting or squeezing a mold part being made thereon.

5. In a mold making machine, in combination, a plurality of sub-machines each comprising a support for a flask or pattern part permitting vertical movement of the part and movement thereof about a horizontal axis, means for moving a part mount-

ed on said support upward, means for suspending the part above said moving means, 15 means for bringing the part supported on one sub-machine above the moving means of another sub-machine, a squeeze head above said supported part when over its moving means, and means for moving said squeeze 20 heads from their position over their respective presses.

In testimony whereof I hereto affix my signature.

JOHN R. WOOD.
